UNITED STATES PATENT OFFICE

163,423

BENCH TYPE MIXER

Frederick W. Schimanski, Cincinnati, Ohio, assignor to Triumph Manufacturing Company, Cincinnati, Ohio, a corporation of Ohio

Application December 8, 1949, Serial No. 6,499

Term of patent 14 years

(Cl. D44—1)

To all whom it may concern:

Be it known that I, Frederick W. Schimanski, a citizen of the United States, residing at Cincinnati, in the county of Hamilton and State of Ohio, have invented a new, original, and ornamental Design for a Bench Type Mixer, of which the following is a specification, reference being had to the accompanying drawings, forming part thereof.

Fig. 1 is a perspective view showing the top, front and one side of a bench type mixer embodying my new design; and

Fig. 2 is an elevational view of the other side thereof.

The rear of the device is substantially plain.

I claim:

The ornamental design for a bench type mixer, as shown and described.

FREDERICK W. SCHIMANSKI.
